(No Model.)

J. F. Mc NUTT.
PAPER FEEDING MACHINE.

No. 605,328.

Patented June 7, 1898.

UNITED STATES PATENT OFFICE.

JOHN F. McNUTT, OF WARREN, OHIO, ASSIGNOR TO THE HARRIS AUTOMATIC PRESS COMPANY, OF NILES, OHIO.

PAPER-FEEDING MACHINE.

SPECIFICATION forming part of Letters Patent No. 605,328, dated June 7, 1898.

Application filed July 2, 1897. Serial No. 643,272. (No model.)

To all whom it may concern:

Be it known that I, JOHN F. McNUTT, of Warren, in the county of Trumbull and State of Ohio, have invented certain new and useful Improvements in Feeders for Printing-Presses; and I do hereby declare the following to be a full, clear, and exact description of the invention, such as will enable others skilled in the art to which it appertains to make and use the same.

This invention contemplates certain new and useful improvements in feeders for printing-presses and the like.

The object of the invention is to provide an extremely simple feeder capable of ready and accurate adjustment for feeding cards, envelops, and the like, of various thicknesses, one at a time, from the bottom of a pile or stack thereof. The feeder can be adjusted both vertically and laterally to accommodate itself to any unevenness or irregularity in the pile or stack.

The invention will be hereinafter fully set forth, and particularly pointed out in the claims.

In the accompanying drawings, Figure 1 is a side elevation showing a portion of the feed-table of a printing-press. Fig. 2 is a view in perspective of the feeder detached. Fig. 3 is a central longitudinal sectional view thereof. Fig. 4 is a bottom plan view of said feeder. Fig. 5 shows a detail.

Referring to the drawings, A designates the feeder as an entirety, and a is a rod having a forward reduced end a', on which a sleeve a² is designed to be loosely held, so as to be free to rotate, by a pin a³, extended through the end of said rod. The forward end a⁴ of sleeve a² is bifurcated to receive the lip b of a head B. This lip is held within the bifurcated end a⁴ by a screw b', which may be loosened to permit of adjustment of said head perpendicularly to the line of movement of rod a. The ends b² of this head being grooved, the same is approximately T shape in plan view.

C is a block the upper surface d of which is inclined, while its under side d' is concaved, the two surfaces terminating in a forward reduced edge d². In the rear wall of this block is a groove or cut-out conforming to the ex-

terior contour of the head B, upon which it is designed to fit, so as to be capable of vertical adjustment. In a recess d³ in the rear wall of this block fits a spring E, which at its lower end bears upon a shoulder e of head B, the tendency of said spring being to elevate the block, so that the upper surface thereof will be in line with the edge e' of head B. The block is rendered adjustable as against the tension of the spring E, so as to increase or diminish the space between its upper surface and the edge e'. This may be accomplished by means of two screws e, working in threaded holes in the block C. The heads e⁴ of these screws are designed to engage the under side of head B. By tightening said screws the block will be lowered as against the tension of its spring. One screw may be adjusted more than the other when it is desired to obtain a greater distance between the surface of the block and the edge of the head at one end than at the other. This is rendered necessary in feeding uneven stock, such as envelops. As each screw is loosened the spring will raise the block until the latter is arrested by the heads of said screws engaging the head B.

In practice the edge of the head forms a shoulder designed to contact with the edge of the article to be fed to the press. The feeding is from the under side of a pile of stock. The block is adjusted so that the distance between the head and the surface of the block will correspond to the thickness of each article of the stack or pile to be fed to the press. By loosening the screw b' the head and block can be adjusted up or down and secured in any desired position. If the stack to be fed should have a downward curve, the head and block must act at an incline, so as to insure the contact of the upper inclined surface of the block against the under side of the pile or stack. If, on the other hand, the stock to be fed is flat and straight, the adjustment should be such as to raise the inclined surface of the block to a practically horizontal position. If the unevenness of the stock warrants, one of the adjusting-screws e³ may be turned a greater or less distance than the other. The sleeve a² being swiveled on the rod a, the feeder is free to move axially thereon to conform to

any irregularity in the stock. Thus not only will the feeder as an entirety conform to the irregularities in the pile of stock, but any unevenness in the articles composing the pile 5 can be compensated for by the greater or less adjustment of one side of the block.

While I do not restrict myself to any special means for operating the feeder, yet I have shown it in Fig. 1 as being located on a feed-table I, the rod *a* being extended through a hollow guide *t* and adjustably secured at its outer end to a sleeve *t'*, carried by a reciprocating carriage *t''*.

I claim as my invention—

- 15 1. A feeder comprising a longitudinally-movable rod, a head mounted on said rod so as to move axially thereon, and having an upper, forward edge forming a shoulder, means for adjusting said head perpendicularly to 20 said rod and a block on the forward end of said head having its inner edge adjacent to said shoulder and tapered on its upper surface toward its outer edge, and means for adjusting said block relatively to said shoulder, substantially as set forth.
- 25 2. A feeder comprising a longitudinally-movable rod, a head mounted on said rod so as to move axially thereon and having an upper forward edge forming a shoulder, a block 30 on the forward end of said head extended in advance of said shoulder and having its upper surface tapered, a spring interposed between said head and block exerting an upward pressure on the latter, and means for 35 adjusting said block at its sides, substantially as set forth.
3. A feeder comprising a longitudinally-movable rod, a head mounted on said rod so as to move axially thereon and having a forward edge, means for adjusting said head perpendicularly to said rod, a block on the forward end of said head extended in advance thereof and having its upper surface inclined, and means engaging the sides of said block 40 for adjusting and holding the same relative to the forward edge of said head, substantially as set forth.
- 45 4. A feeder comprising a longitudinally-movable rod, a sleeve loose on said rod so as

to move axially thereon, a head from which 50 said sleeve extends having an upper forward edge forming a shoulder, a block on said head having an upper inclined surface, said block being extended in advance of said head, a spring interposed between said head and 55 block exerting an upward pressure on the latter, and screws carried by said block at its sides for adjusting said block bodily or at either side, as set forth.

5. A feeder comprising a longitudinally-movable rod, a sleeve loose on said rod and having a bifurcated end, a head adjustably held to said bifurcated end and having a forward edge forming a shoulder, and a block on said head capable of being raised and lowered 65 thereon, substantially as and for the purpose stated.

6. The combination with the rod, of the head mounted on said rod having forward grooved ends and an upper forward edge 70 forming a shoulder, a block having its upper surface inclined and formed with a longitudinal recess to accommodate said head, a spring between said head and block bearing upwardly on the latter, and screws carried by 75 said block at its sides and engaging said head, whereby the block may be adjusted bodily or at either side, substantially as set forth.

7. The combination with the rod, of a sleeve swiveled thereon having a bifurcated 80 end, a head having a lip, and a screw adjustably holding said lip within said bifurcated end, a block fitted on said head so as to be moved up and down thereon, said block having its upper surface inclined, a spring fitting in a recess of said block and bearing at one end against a shoulder of said head, and screws carried by said block and engaging 85 said head for adjusting the former, substantially as set forth.

In testimony whereof I have signed this specification in the presence of two subscribing witnesses.

JOHN F. McNUTT.
